United States Patent

Des. 237,769
Patented Nov. 25, 1975

237,769

FURNITURE SUBFRAME

William R. Curtis, New Castle, and David C. Trimble, Yorklyn, Del., assignors to Hercules Incorporated, Wilmington, Del.

Continuation-in-part of design application Ser. No.
506,674, Sept. 17, 1974, which is a division of design application Ser. No. 455,773, Mar. 28, 1974.
This application Sept. 27, 1974, Ser. No. 509,887

Term of patent 14 years

Int. Cl. D6—06

U.S. Cl. D6—197

FIG. I

FIG. 2

FIG. 1 is a perspective view of the front of the furniture subframe of the instant invention.

FIG. 2 is a perspective view of the back view of the furniture subframe of the instant invention.

This is a continuation-in-part of application Ser. No. 506,674, filed Sept. 17, 1974, which in turn is a division of application Ser. No. 455,773, filed Mar. 28, 1974.

We claim:

The ornamental design for a furniture subframe, as shown.
